UNITED STATES PATENT OFFICE.

HENRY F. BECHMAN, OF BATTLECREEK, MICHIGAN, ASSIGNOR TO THE DUPLEX PRINTING PRESS COMPANY, OF BATTLECREEK, MICHIGAN.

WEB-MANIPULATING MECHANISM.

No. 811,121.

Specification of Letters Patent.

Patented Jan. 30, 1906.

Application filed May 24, 1904. Serial No. 209,525.

To all whom it may concern:

Be it known that I, HENRY F. BECHMAN, of Battlecreek, in the county of Calhoun and State of Michigan, have invented certain new and useful Improvements in Web-Manipulating Mechanism; and I hereby declare that the following is a full, clear, and exact description thereof, reference being had to the accompanying drawings, which form part of this specification.

This invention is an improved means or mode of handling long webs parts of which have to be intermittently stopped for operations thereon, while the remaining portions of the webs may be fed toward and from the operating-point by continuously-acting mechanisms, such mode of operation being usually employed in stationary-bed reciprocating-cylinder web-printing machines, such as the well-known duplex flat-bed web-perfected machines in which the web is continually fed into the press and continuously delivered therefrom, while the part being printed is momentarily stopped during the printing operation.

In particular, my invention relates to machines in which the same web is fed twice past a single printing-couple, such as a co-acting bed and cylinder, to receive two or more impressions—for instance, where a web is to be perfected or printed in colors, such presses being known in the art—and the web after having passed through the printing-couple is deflected to one side and returned through the same printing-couple, the two leads of web through such couple being side by side. Heretofore in this style of machines the web is fed in at one end of the press, carried between the printing-couple, then deflected to one side, with or without reversing, and led back through the printing-couple to the delivery. In order to deflect the web from its original path to an adjacent path, deflectors (usually consisting of angularly-arranged bars or rollers) are employed, and in practically operating such machines great difficulty is experienced in keeping the leads of the web in alinement, as the alternate stopping and starting of the web between the feed and delivery causes alternate slackening and tautening of the web, which results in a lateral movement of the web in the deflector, causing imperfect registration, and where the

printing-couple consists of a stationary bed and reciprocating cylinder this lateral shift of the web is enhanced by the additional slackening and tautening of the web caused by the reciprocations of the cylinder, and the trouble is further increased by the use of looping-rollers. In fact, I have found it impossible to keep the two lengths of the web in perfect alinement by any known means when operating at a high speed on an intermittently-shifted web turned over angle-bars or deflected from one plane to another between the feed and delivery. The present invention overcomes the difficulties heretofore experienced in such machines in a very simple manner; and it consists, briefly, in using a double feed and double delivery and deflecting the web between the first delivery and second feed. In other words, instead of attempting to deflect the web in the press proper I deflect it outside the press proper, so that the portions or leads of the web in the press travel always in a straight web-path.

The invention will be explained in detail in connection with the accompanying drawings and summarized in the claims:

Figure 1 of the drawings is a detail sectional diagram of a machine adapted to handle the web in accordance with my invention. Fig. 2 is a detail top plan view of Fig. 1.

I have illustrated the invention as applied to a single-bed and single-cylinder web-press, the general arrangement of web feeding, delivering, looping, and printing mechanisms being similar to those of the well-known duplex press, the invention being useful in connection with a single bed and cylinder press or with presses having a plurality of beds, as will be readily understood by those familiar with this class of machines. I do not therefore, restrict myself to any particular form or type of press or other web-handling machine.

In the drawings, 66 represents a bed, 6 a reciprocating cylinder coacting therewith and actuated by a pitman 66 and crank-wheel 67, as indicated in dotted lines in Fig. 1, substantially as shown and described in Cox's patent, No. 478,503, of July 2, 1892.

21, 22 are web-guides at each side of the cylinder.

5 and 8 are web-looping rollers, which are supported by vertically-movable bars 55, operated by a vibrating lever 56 and cam 57.

19 and 20 are fixed web-guides coacting with looper 5, and 23-24 are similar web-guides coacting with looper 8.

The web-feeding mechanism comprises a set of rollers 3, 31, 16, and 39 and coacting tapes 161 and 331. The tapes 331 run over rollers 16-31-3, under roller 39, back to roll 16, and occupy about half the length of said rollers. The tapes 161 run over roll 16, under roller 3, around roller 39, back to roll 16, and occupy the remaining half of the length of said rolls.

The delivery mechanism comprises rolls 9, 91, 92, and 39 and coacting tapes 99, which run from roller 91, over roller 39, around roller 92, over roll 9, back to roller 91. The tapes 99 may alternate with the tapes 161 on roll 39.

The web-deflector, as shown, is composed of transverse guides 11 and 15, angle-guides 12 and 14, and longitudinal guide 13, and at proper points are stationarily located web-guides 2, 7, 10, and 17.

The bed and cylinder, the looping-rollers 5 and 8, and the web feeding and delivery mechanisms may be constructed and operated as to time substantially like the printing, looping, feeding, and delivery mechanisms of the duplex press, and the following explanation of the course of the web will enable any one familiar with such machines to understand my present invention. The web passes from roll 1, over guide 2, around guide 3, over guide 4, down and around guide 19, up and over the looper or equalizer roller 5, down and around guide 20, over and around coaxer-roll 7, to and over guide 21, down under cylinder 6, up over guide 22, over guide 23, down and around the looper or equalizer roller 8, up and over guide 24, over delivery-roll 9, around guide 10, up and over guide 11, around and over angle-bar 12, then over and around roll 13, back over and under angle-bar 14, to, over, and around roll 15. When the web reaches roll 15, it will have been transferred from the left hand or side of the press to the right hand or drive side and is now in position to start back into the press on the drive side, and therefore it is led from roll 15 to and over roll 16, around a portion of roll 3, over idler-roll 4, down and around guide 19, up and over the looper or equalizer roller 5, down and around the guide 20, thence over and around coaxer-roll 7, over guide 21, down under cylinder 6, up over guide 22, to, and over guide 23, down and around the looping-roller 8, up over guide 24, around delivery-roll 9, out and around roll 10, up and over roll 17, over to and around portion of roll 18, which is one of the usual set of rolls at top of the folder-former, and the web passes from roller 18 over the former and into the folder.

From the foregoing and the drawings it will be observed that the web is led twice

through the printing-couple, that the two lengths of web in the press from the feed to the delivery are exactly parallel, that both lengths of web between the feed and delivery run or move in a continuous direct web-line, and that in the instance shown both leads of web travel alike—that is, both the lengths of narrow web in the press travel as one web from feed to the delivery—and that the narrow web is deflected from the right to left hand side of press outside the feed and delivery mechanisms. This last is the principal and essentially novel feature of my invention. In other machines the web is deflected from one side to the other intermediate the feed and delivery mechanisms and the printing mechanisms—that is, the deflecting or turning mechanism is located to act on the web between the point where it is fed in and the point where it is delivered—and therefore the web on the deflector is subjected to intermittent movements.

By my invention it will be noted the web runs continuously over the deflector, and the latter is located practically outside the press and between the points of first delivery and second infeed of the web. By this improved method of handling the web I am able to lead a narrow web a plurality of times through the machine with absolute precision, so that perfect registration is obtainable at high speeds and with less liability of rupture of web, owing to its continuous movement over the deflector.

Having thus described my invention, what I claim as new, and desire to secure by Letters Patent thereon, is—

1. In combination, a stationary type-bed, an impression-cylinder and means for rolling the cylinder back and forth over the bed, means for feeding a narrow web twice into the press, and means for delivering such web twice from the press, and looping devices for intermittently shifting the part of the web in the press between the feeding and delivering mechanisms through the printing devices; with means for guiding a narrow-width web twice through the press between the feeding and delivering devices; with means for deflecting the web to one side, between the points where it first leaves the delivery, and where it enters the feed devices a second time, substantially as described.

2. In combination, a stationary bed and reciprocating cylinder for printing upon a web, and means for reciprocating the cylinder; means for continuously feeding web to said printing means, means for delivering the web from said printing means, and web-looping mechanism for intermittently shifting the web between said feeding and delivery mechanisms; with a web-deflector adjacent to the feeding and delivering mechanisms by which the web after passing once through the

machine is deflected to one side, and again directed to the feeding mechanism and through the machine in a plane parallel with its first travel therethrough, substantially as described.

3. In a printing-press the combination of a web-printing couple comprising a stationary bed and a reciprocating impression-cylinder, and means for reciprocating the cylinder, a single continuously-acting means for feeding web into the press, a single means for continuously delivering web from the press, and a set of looping devices adapted to intermittently shift the portions of web in the press between the feeding and delivering mechan-

ism through the printing devices; with means for directing a narrow-width web twice through the printing-couple, and means for deflecting the web to one side after it first leaves the press-delivery mechanism and directing it a second time into the feeding mechanism and through the press, substantially as described. 20

In testimony that I claim the foregoing as my own I affix my signature in presence of 25 two witnesses.

HENRY F. BECHMAN.
